UNITED STATES PATENT OFFICE

VIRGIL O. JONES, OF DECATUR, ILLINOIS, ASSIGNOR OF ONE-HALF TO WILLIAM C. JONES, OF NIANTIC, ILLINOIS

WATER HEATER OR BOILER

Application filed June 5, 1926. Serial No. 113,874.

This invention relates to improvements in water heaters or boilers and the principal object thereof is the provision of a structure which will efficiently and effectively heat water to a high degree of temperature without the necessity of the use of a plurality of tubes, sections and the like. The apparatus may be designed for coal, gas or oil burning and for hot water, steam and pressure tank heating for home or domestic use as well as for business and public building use, and also may be used for generating steam for power purposes.

Another object of the invention is the provision of such a construction which is simple and readily made and assembled and may be formed in sections so as to facilitate installations of the larger constructions and also including the other advantages herein-after set forth at length.

To the accomplishment of the foregoing and such other objects as may hereinafter appear, this invention consists in the construction, combination and arrangement of parts hereinafter described and then sought to be defined in the appended claims, reference being had to the accompanying drawings forming a part hereof and which show, merely for the purpose of illustrative disclosure a preferred embodiment of my invention, it being expressly understood, however, that various changes may be made in practice within the scope of the claims without digressing from my invention idea.

25 In the drawings—

Figure 1 is a vertical sectional view of heater constructed to embody my invention, parts being shown in elevation to facilitate the disclosure.

40 Figure 2 is a horizontal cross section on line B—B of Figure 1 showing the front half of the construction only.

Figure 3 is a top plan view of the secondary combustion chamber 5 and associated parts with the dome plate 17 removed.

45 Figure 4 is a vertical transverse cross section taken substantially on line D—D of Figures 1 and 3.

Referring now to the drawings the numer- 50 al 1 designates a casing which may be of any

size or shape and may be sectional or made in as few pieces or parts as possible. It is provided with the customary appurtenances for firing operation including the grate, fire pot, ash pit and the like, these parts not being shown because they form no part of my invention. However, 2 designates the ash pit door and 3 the fire door.

Mounted within this casing 1 are the water heating casings or elements which include the combustion chamber 4, a secondary combustion chamber 5 connected with the first-mentioned combustion chamber 4 by means of upwardly extending flue 6, an outlet pipe or conduit 7 communicating with the secondary combustion chamber 5 by means of flue 8; the outlet flue 7 also communicates with the upwardly extending flue 6 as at 9 and has the damper 10 provided adjacent the junction therewith. The position of the damper is 70 regulated by the adjusting means 11. The combustion chamber 4 has its top or crown sheet 12 bent or formed with a downwardly curved portion 13 where the upwardly extending flue 6 fits the opening into the combustion chamber 4, for the purpose of directing the hot gases and products of combustion downwardly, as indicated by the arrows, before egress through the upwardly extending flue 6. The joints of all of these parts are 75 watertight so that the outer casing is filled with water, which has contact with all of heated casings or elements, as shown particularly in Figure 1 of the drawing.

The secondary combustion chamber 5 is 80 a very important feature of this invention. It includes a flat bottom plate or member 14 having the opening 15 at one end to communicate with the upwardly extending flue 6 and the opening 16 at the other end to 85 communicate with the flue 8. This plate 14 is of substantially ovoid shape (see Figure 3) and the opening 15 is much larger in cross sectional area than the opening 16. These openings correspond in size to the cross sec- 90 tional areas of the flues 6 and 8, the flue 6 being much greater in cross sectional area than the flue 8. The dome plate or member 17 is shaped to fit the bottom plate 14 and is 95 semi-circular in vertical transverse section 100

(see Figure 4). This secondary combustion chamber is adapted to receive the hot gases and products of combustion from the primary or main combustion chamber and becomes very hot and as the surface area of the same is comparatively large, a large quantity of heat is absorbed by the water which entirely surrounds the same. In order to facilitate the heating of this secondary combustion chamber and to provide combustion therein, I find it desirable to introduce fresh air or oxygen. This is done by means of an air inlet pipe or conduit 18 which has its inlet end 19 extending without the casing 1, the pipe or conduit 18 extending for the major portion of its length along the side of the flue 6 until it enters the secondary combustion chamber 5 where it is bent or curved as at 20 (see Figures 1 and 3, respectively). The inlet end 19 may be controlled by any suitable damper (not shown) and it is therefore seen that air being drawn into the pipe or conduit 18 passes upwardly therethrough and is discharged therefrom in a whirling or turning motion so that it mixes with the hot gases and products of combustion, which are comparatively slowly passing through the secondary combustion chamber 5 due to the fact that the inlet flue is of greater size than the outlet flue, and, therefore, the rate of discharge is less than the rate of inlet. The pipe or conduit 18 may be of various shapes but I have found that if it is flattened or of considerable width, as shown in Figure 3 of the drawing, better results are obtained.

This construction results in very rapid heating of the water as all of the heating surfaces of the casings or elements are in contact with the water which substantially surrounds all of the surfaces, thereby giving the greatest possible area of contact between the water and the heating surfaces. The construction of the combustion chamber crown sheet or top plate causes the gases and products of combustion to be directed back down over the fire and thus causes what might be termed a second combustion of the individual particles which otherwise would pass directly into the flue 6. The hot gases and products of combustion then pass through flue 6 into the secondary combustion chamber 5 through which they pass relatively slowly and are subjected to the whirling action of the fresh air or oxygen and mixing therewith produces a secondary combustion. These hot gases and products of combustion then pass downwardly through the flue 8 into the outlet flue 7. This outlet flue 7 has a direct connection with the upwardly extending flue 6 which is open when firing or shaking down the ashes, as is well understood.

What I claim is:—

1. A heater of the character described including, in combination the following elements, a heater casing, a combustion chamber

therein, a secondary combustion chamber located above said first-mentioned combustion chamber, an upwardly extending flue connected to said two combustion chambers, an outlet flue, a connection from said secondary chamber to said outlet flue, all of said parts having watertight joints and adapted to be surrounded with water within the casing so that the water is heated by contact with the walls of the combustion chambers and the flues specified, an air supply conduit entering said upwardly extending flue near the bottom thereof and extending along the side of the same and having an open end within said secondary combustion chamber.

2. A heater of the character described including, in combination the following elements, a heater casing, a combustion chamber therein, a secondary combustion chamber located above said first-mentioned combustion chamber, an upwardly extending flue connected to said two combustion chambers, an outlet flue, a connection from said secondary chamber to said outlet flue, all of said parts having watertight joints and adapted to be surrounded with water within the casing so that the water is heated by contact with the walls of the combustion chambers and the flues specified, an air supply conduit entering said upwardly extending flue near the bottom thereof and extending along the side of the same and having an open end within said secondary combustion chamber, said discharge end being curved so as to direct the discharge of the air in a curved path into said secondary combustion chamber.

3. A heater of the character described including, in combination the following elements, a heater casing, a combustion chamber therein, a secondary combustion chamber located above said first-mentioned combustion chamber an upwardly extending flue connected to said two combustion chambers at the side thereof, an outlet flue, a connection from said secondary chamber to said outlet flue, all of said parts having watertight joints and adapted to be surrounded with water within the casing so that the water is heated by contact with the walls of the combustion chambers and the flues specified, said first-mention combustion chamber having a crown plate shaped so as to direct a substantial part of the products of combustion downwardly over the fire before entry into said upwardly extending flue, this construction being provided by diverging downwardly a portion of the crown plate adjacent one edge of said upwardly extending flue.

4. A heater of the character described including, in combination the following elements, a heater casing, a combustion chamber therein, a secondary combustion chamber located above said first-mentioned combustion chamber, an upwardly extending flue

connected to said two combustion chambers, an outlet flue, a connection from said secondary chamber to said outlet flue, all of said parts having watertight joints and adapted to be surrounded with water within the casing so that the water is heated by contact with the walls of the combustion chambers and the flues specified, said outlet flue having a direct connection with said upwardly extending flue and a damper interposed at the junction of said outlet flue with said upwardly extending flue.

5. A heater of the character described including, in combination the following elements, a heater casing, a combustion chamber therein, a secondary combustion chamber located above said first-mentioned combustion chamber, an upwardly extending flue connected to said two combustion chambers, 10 an outlet flue, a connection from said secondary chamber to said outlet flue, all of said parts having watertight joints and adapted to be surrounded with water within the casing so that the water is heated by contact 25 with the walls of the combustion chambers and the flues specified, said secondary combustion chamber being of a general ovoid shape in horizontal cross section with the larger end connected to said upwardly extending flue and the smaller end communicating with said connection to said outlet flue.

6. A heater of the character described including, in combination the following elements, a heater casing, a combustion chamber therein, a secondary combustion chamber located above said first-mentioned combustion chamber, an upwardly extending flue connected to said two combustion chambers, an outlet flue, a connection from said secondary 35 chamber to said outlet flue, all of said parts having watertight joints and adapted to be surrounded with water within the casing so that the water is heated by contact with the walls of the combustion chambers and the flues specified, said secondary combustion chamber being of a general ovoid shape in horizontal cross section with the larger end connected to said upwardly extending flue and the smaller end communicating with said 40 connection to said outlet flue and also being semi-circular in vertical transverse cross section.

7. A heater of the character described including, in combination, a casing adapted to be entirely filled with water and having a combustion chamber therein, a secondary combustion chamber therein located above said first-mentioned combustion chamber, a flue element extending upwardly and directly 45 connected to said combustion chambers, an outlet flue and a connection from said secondary combustion chamber to said outlet flue, said secondary combustion chamber including a flat bottom plate and a dome plate or member semi-circular in vertical trans-

verse cross section, said bottom plate being ovoid in shape and having an opening at one end to receive the upwardly extending flue and having a smaller opening at the other end for the connection to the outlet flue.

8. A heater of the character described including, in combination, a casing adapted to be entirely filled with water and having a combustion chamber therein, a secondary combustion chamber therein located above 70 said first-mentioned combustion chamber, a flue element extending upwardly and directly connected to said combustion chambers near the sides thereof, an outlet flue and a connection from said secondary combustion chamber to said outlet flue, said first-mentioned combustion chamber having its crown plate shaped so as to direct a substantial part of the products of combustion downwardly over the fire before entry into said upwardly extending flue.

9. A heater of the character described including, in combination, a heater casing, a combustion chamber therein having a flue opening at one side with the crown plate 75 turned downwardly adjacent the flue opening so as to direct the products of combustion downwardly over the fire before entry into said upwardly extending flue, a secondary combustion chamber within the casing located above said first-mentioned combustion chamber, an upwardly extending flue connected to said first-mentioned combustion chamber and to one end of said secondary combustion chamber, said secondary combustion chamber being formed of two parts, one 80 a flat base plate and the other a dome semi-circular in vertical transverse cross section, an outlet flue and a connection from said secondary combustion chamber to said outlet flue, said elements all having water-tight joints and the casing being adapted to be filled with water which substantially surrounds all of the surfaces of the elements.

10. A heater of the character described including, in combination, a heater casing, a combustion chamber therein having a flue opening at one side with the crown plate 85 turned downwardly adjacent the flue opening so as to direct the products of combustion downwardly over the fire before entry into said upwardly extending flue, a secondary combustion chamber within the casing located above said first-mentioned combustion chamber, an upwardly extending flue connected to said first-mentioned combustion chamber and to one end of said secondary combustion chamber, said secondary combustion chamber being formed of two parts, one 90 a flat base plate and the other a dome semi-circular in vertical transverse cross section, an outlet flue and a connection from said secondary combustion chamber to said outlet flue, said outlet flue extending horizontally into said casing and also having a connection 95 100 105 110 115 120 125 130

with said upwardly extending flue, said elements all having water-tight joints and the casing being adapted to be filled with water which substantially surrounds all of the surfaces of the elements.

5 In testimony that I claim the foregoing, I have hereunto set my hand this 7th day of May, 1926.

VIRGIL O. JONES.
